Application August 21, 1953, Serial No. 375,638

4. Claims. (Cl. 121—17)

This invention relates to vibrators and, more particularly, to a novel, improved pneumatic vibrator and a starting system therefor.

Vibrators of the pneumatic type generally comprise a cylinder having a relatively massive piston reciprocable therein, and include means for applying fluid pressure alternately to opposite ends of the piston to effect such reciprocation. Due to the relatively high inertia of the piston, the piston remains stationary and the cylinder is reciprocated relative to the piston. To utilize such vibration or reciprocation of the cylinder, the latter is attached to the structure to be vibrated and may be resiliently supported for axial reciprocation.

When such pneumatic vibrators are positioned for vibration in a substantially horizontal plane, special starting arrangements are incorporated. One arrangement which is widely used involves a "starting" spring which, when the pressure fluid supply is cut off, biases the piston to one end of the cylinder. Thus, when the vibrator is restarted, the pressure fluid is admitted to such one end of the cylinder first. In another known arrangement, a spring positioned valve is provided to assure the proper sequence of pressure fluid application in starting the vibrator.

The foregoing starting arrangements are generally satisfactory in normal operation but, over relatively long periods of time, spring breakage becomes an important maintenance factor. The spring breakage is accelerated when these pneumatic vibrators are used in heavy duty applications or under severe operating conditions.

A typical example of such conditions is represented by the use of pneumatic vibrators to periodically shake or vibrate suspended tube sections of a vapor generator to dislodge combustion-gas-deposited solids from the tube surfaces. Due to the relatively high ambient temperatures involved in installations of this type, vibrators incorporating starting springs are unsatisfactory due to the necessity for frequent spring replacement. This is not only costly in time and labor but also increases the "down time" of the vibrator with consequent potential buildup of deposited solids to a point affecting efficient operation of the generator section.

As a solution of these difficulties, the present invention provides a pneumatic vibrator in which no "starting" springs or spring operated starting valves are used. The two pressure fluid inlet ports in the cylinder side wall, respectively selectively communicating with opposite ends of the cylinder, are provided with separate valve controlled supply lines connected to the source of pressure fluid. In starting the vibrator, only one valve is opened initially, thus providing initial fluid pressure application to only one end of the cylinder. After a preset time interval, for example 3 seconds, the second valve is opened. Both valves then remain open during the vibrating period, which may continue for a preselected time duration.

In a practical application, the second valve is operated by time delay means activated simultaneously with operation of the first valve. The first valve, and the time de-

lay means, are, in turn, preferably operated by a timer combination which periodically initiates operation of the vibrator at preset times, and maintains the vibrator operating for a predetermined interval.

For an understanding of the invention principles, reference is made to the following description of a typical practical embodiment thereof as illustrated in the accompanying drawings.

In the drawings:

Fig. 1 is an axial sectional view through a pneumatic vibrator embodying the invention and schematically indicating the pressure fluid supply lines;

Fig. 2 is a diametric sectional view on the line 2—2 of Fig. 1;

Fig. 3 is a partial elevation view of a vapor generator suspended tube bank having the invention vibrator attached thereto; and

Fig. 4 is a schematic wiring diagram of the vibrator starting and timing system.

Referring to Figs. 1 and 2, the invention pneumatic vibrator 10 comprises a cylinder 20 in which is reciprocably mounted a relatively massive, high inertia piston 40. Cylinder 20 comprises a cylindrical wall 21, with longitudinal reinforcing ribs 22 extending therealong, and integral end flanges 23 formed with bolt openings 24 at each corner. This integral structure is assembled with imperforate or closed end walls 25, 25 by means of bolt and nut assemblies 26 extending through both walls 25 and through the holes 24 in flanges 23, gaskets 27 being interposed between each flange 23 and the adjacent end wall 25. The end walls 25 are angular, having legs or flanges 28 provided with openings 31 to receive bolts 32 for attachment of the vibrator to a support 33 (Figs. 1 and 3).

Side wall 21 has formed therethrough inlet ports 30a, 30b and exhaust ports 35a, 35b, the inlet ports each having an enlarged, threaded recess 34 for connection of a pressure fluid line thereto. As best seen in Fig. 2, each inlet port includes a series of drilled passages 36 at the inner end of recess 34, and each exhaust port comprises dual, circumferentially spaced passage 37, 37.

The inlet ports 30a and 30b are spaced equal distances from adjacent end walls 25, and exhaust ports 35a and 35b are intermediate the inlet ports and symmetrically located relative to the mid-point of the cylinder. The purpose of these dispositions will be explained hereinafter.

Piston 40 is formed with reduced end sections 41a and 41b and a pair of circumferential grooves 45a, 45b spaced axially from each other a distance substantially less than the axial spacing of inlet ports 30a, 30b but greater than the axial spacing of exhaust ports 35a, 35b. The groove 45a is connected by three radial passages 42a to three longitudinal passages 43a extending through end 41a. Similarly, three radial passages 42b connect groove 45b to three longitudinal passages 43b extending through end 41b.

In the position illustrated in Fig. 1, piston 40 is at the left end of cylinder 20, and groove 45a registers with inlet port 30a. This is one of several possible "starting" positions of the vibrator. As schematically illustrated in Fig. 1, a pressure fluid supply line 51, controlled by a valve 50, is connected to port 30a, and a separate pressure fluid supply line 56, controlled by a valve 55, is connected to port 30b.

To start the vibrator from the position shown in Fig. 1, control valve 50 is opened, admitting pressure fluid through line 51, inlet port 30a, groove 45a, and passages 42a, 43a to the left end of piston 40. Piston 40 is thus forced to the right, it being noted that groove 45b is registered with exhaust port 35b when piston 40 is at the left end of the cylinder 20. As piston 40 moves to the right, inlet port 30a and exhaust port 35b are blocked off, but piston movement continues, due to the inertia of the

piston, to register groove 45a with exhaust port 35a and groove 45b with inlet port 30b.

Meanwhile, a preset time interval after valve 50 is opened, valve 55 is opened to admit pressure fluid through line 56 to inlet port 30b. Thus, as groove 45b registers with port 30b, pressure fluid is admitted through groove 45b and passages 42b, 43b to the right end of the piston. Consequently, as piston 40 approaches the right end of the cylinder, pressure is building up at this end while being exhausted from the left end through the registry of groove 45a with exhaust port 35a.

The piston is now forced to the right, cutting off port 30b and then registering groove 45b with exhaust port 35b. The cycle now repeats, both valves 50 and 55 remaining open during the desired operating period of the vibrator. To stop the vibrator, both control valves are closed. Re-starting is always effected by first opening only the valve 50 and then opening valve 55 a preset time after valve 50 is opened, for example 3 seconds.

If it is assumed that piston 40 has stopped in mid position, or equi-distant from both ends of cylinder 20, the drilled inlet passages 36 for ports 30a and 30b will be adjacent to the piston grooves 45a and 45b, as will also be the exhaust passages 35a and 35b. Piston 40 has running clearance in cylinder 20, as will be understood by those skilled in the art. Thus, when control valve 50 is opened to supply air through line 51 to inlet port 30a and through the drilled passage 36 communicating therewith, the air will flow between the piston and cylinder in the clearance space therebetween. At least some of this air will flow through passages 42a and 43a to the left end of the piston and some of the air will flow toward exhaust port 35a through piston groove 45a. Due to the fact that the inlet ports are located on the opposite side of the cylinder from the exhaust port, the entering air under pressure displaces the piston 40 toward the exhaust ports, pressing it against cylinder wall 21 to effectively increase the resistance to flow of air to the exhaust ports. Accordingly, the air pressure is effectively exerted in the cylinder on the left face of the piston, increasing the pressure on this face and forcing the piston to the right. After a short movement to the right, cylinder groove 45b will register with passage 36 of inlet port 30b. After the preset time interval, valve 55 opens and air will flow through line 56 to inlet port 30b and thus through passage 36, groove 45b and passages 42b and 43b to the right end of the cylinder forcing the piston 40 to the left. With both valves 50 and 55 now open, operation of the piston proceeds in the manner previously described.

Should the piston 40 have stopped at the right end of cylinder 20, when valve 50 is opened the air entering through port 30a will again flow into the clearance between the piston and cylinder, pushing the piston toward the exhaust ports, and also flowing through groove 45a through exhaust port 35a. The piston remains substantially stationary until valve 55 opens after the preset time interval. When valve 55 opens, the air will flow through inlet port 30b to the right end of the piston to move the piston to the left, the air entering through port 30a being ineffective to resist this movement due to the communication between groove 45a and exhaust port 35a.

Fig. 3 illustrates a typical installation of vibrator 10. The member 33 is a sleeve having a rod 61 telescopically therethrough with its inner end connected to one or more tubes 62 of a heat exchanger section 60, such as a superheater section of a steam generator. Blocks 63 on member 33 are positioned against each leg 28 of end walls 25, and a bracket 64 connects rod 61 to tubes 62.

The sleeve 33 is mounted through a liner 65 in a port through the casing wall 66 of the steam generator, being supported from liner 65, with leakage of air through the opening between member 33 and liner 65 prevented by seam member 67. The outer end of sleeve 33 is suspended, by a spring 68, from a supporting framework partially illustrated at 70, spring 68 being secured to a

collar 71 on sleeve 33. A coil spring 72 surrounds the outer end of rod 61, seated at one end against collar 71 and at the other end against a spring seat 73 adjustably positioned along rod 61 by nuts 74 threaded on the rod.

In operation, as piston 40 is reciprocated relative to cylinder 20, the piston remains substantially stationary due to its relatively large inertia, and the cylinder is vibrated. This vibration is transmitted to sleeve 33 and rod 61, and thus to tubes 62. The latter are thus vibrated to dislodge combustion-gas-deposited solids from their surfaces.

Referring to Fig. 4, a preferred electrical control system for starting the vibrator at periodic intervals and operating the vibrator for a set time duration each time it is started, is illustrated as energized from conductors 76, 76 connected across an A. C. supply through switches 75 ganged for conjoint operation. When switches 75 are closed, a timer 77 is energized, this timer having an indicating lamp 78 connected in parallel with its motor 79. The latter, through suitable reduction gearing, drives a cam 81 which periodically closes a normally open switch

82. When switch 82 is closed, it energizes a duration of operation timer 80. This timer has a clutch 83 which, after a preset interval of operation, opens normally closed switches 84, 86. Switch 84 is in series with the motor 87 of timer 80 and switch 86 is in series with a relay 90. Thus, when switch 82 closes, relay 90 is energized to close its contacts 91. These contacts are in series with solenoid valve 50 in supply line 51, and also in series with a time delay relay 95. An indicating lamp 92 is in shunt with valve 50.

After a time delay of from 3 to 20 seconds, relay 95 closes its contacts 96 which are in series with solenoid valve 55 in supply line 56, and having an indicating lamp 97 in shunt therewith. Vibrator 10 is started by the opening of valve 50, and continues to vibrate as long as valves 50 and 55 remain open, valve 55 being opened by time delay relay 95 preferably 3 seconds after valve 50 is opened by closing of relay contacts 91.

After an operating period of up to 60 seconds, clutch 83 opens switches 84, 86 to stop timer 80 and drop relay 90. When relay 90 drops, opening of contacts 91 closes valve 50 and drops relay 95. Opening of relay contacts 96 closes valve 55. The vibrator then stops until the interval timer 77 again closes contacts 82 to re-start the vibrating cycle.

While a specific embodiment of the invention has been shown and described in detail to illustrate the application of the invention principles, it will be understood that the invention may be embodied otherwise without departing from such principles.

What is claimed is:

1. A pneumatic vibrator comprising, in combination, 55 a cylinder having closed end walls; a relatively massive piston reciprocably mounted in said cylinder; first and second inlet ports in the side wall of said cylinder; first passage means in said piston opening through one end thereof and communicating with said first port when said 60 one end of the piston is adjacent the corresponding end of said cylinder; second passage means in said piston opening through the opposite end thereof and communicating with said second port when said opposite end of the piston is adjacent the opposite end of said cylinder; 65 exhaust port means in the side wall of said cylinder intermediate said inlet ports; first valve means selectively operable to connect a source of pressure fluid to said inlet port to move said piston toward such opposite end of said cylinder to initiate relative reciprocation between 70 said piston and cylinder to vibrate said cylinder; second valve means operable to connect a source of pressure fluid to said second inlet ports; time delay means activated upon operation of said first valve means to operate said second valve means a preset time interval after 75 operation of said first valve means; and a cyclically op-

erable timer operatively associated with said first valve means and said time delay means to periodically and simultaneously operate said first valve means and activate said time delay means for a predetermined time interval.

2. A pneumatic vibrator comprising, in combination, a cylinder having closed end walls and constructed for connection to a structure to be vibrated; means mounting said cylinder for axial reciprocation; a relatively massive piston reciprocably mounted in said cylinder; first and second inlet ports in the side wall of said cylinder; first passage means in said piston opening through one end thereof and communicating with said first port when said one end of the piston is adjacent the corresponding end of said cylinder; second passage means in said piston opening through the opposite end thereof and communicating with said second port when said opposite end of the piston is adjacent the opposite end of said cylinder; first valve means selectively operable to connect a source of pressure fluid to said first inlet port to move said piston toward such opposite end of said cylinder to initiate relative reciprocation between said piston and cylinder to vibrate said cylinder; second valve means operable to connect a source of pressure fluid to said second inlet port; time delay means activated upon operation of said first valve means to operate said second valve means a preset time interval after operation of said first valve means; and a cyclically operable timer operatively associated with said first valve means and said time delay means to periodically and simultaneously operate said first valve means and activate said time delay means for a pre-determined time interval.

3. A pneumatic vibrator comprising, in combination, a cylinder having closed end walls; a relatively massive piston reciprocably mounted in said cylinder; first and second inlet ports in the side wall of said cylinder; first passage means in said piston opening through one end thereof and communicating with said first port when said one end of the piston is adjacent the corresponding end of said cylinder; second passage means in said piston opening through the opposite end thereof and communicating with said second port when said opposite end of the piston is adjacent the opposite end of said cylinder; exhaust port means in the side wall of said cylinder in-

termediate said inlet ports; a first solenoid valve selectively operable to connect a source of pressure fluid to said first inlet port to move said piston toward such opposite end of said cylinder to initiate relative reciprocation between said piston and cylinder to vibrate said cylinder; a second solenoid valve operable to connect a source of pressure fluid to said second inlet port; and time delay means energized simultaneously with said first solenoid valve to energize said second solenoid valve a pre-set time interval after energization of said first solenoid valve.

4. A pneumatic vibrator comprising, in combination, a cylinder having closed end walls; a relatively massive piston reciprocably mounted in said cylinder; first and second inlet ports in the side wall of said cylinder; first passage means in said piston opening through one end thereof and communicating with said first port when said one end of the piston is adjacent the corresponding end of said cylinder; second passage means in said piston opening through the opposite end thereof and communicating with said second port when said opposite end of the piston is adjacent the opposite end of said cylinder; exhaust port means in the side wall of said cylinder intermediate said inlet ports; a first solenoid valve selectively operable to connect a source of pressure fluid to said first inlet port to move said piston toward such opposite end of said cylinder to initiate relative reciprocation between said piston and cylinder to vibrate said cylinder; a second solenoid valve operable to connect a source of pressure fluid to said second inlet port; time delay means energized simultaneously with said first solenoid valve to energize said second solenoid valve a pre-set time interval after energization of said first solenoid valve; and a cyclically operable timer operatively associated with said first solenoid valve and said time delay means to periodically and simultaneously energize said first solenoid valve and said time delay means for a pre-determined time interval.
